(57) **CLAIM**

The ornamental design for a wick, as shown and described.

DESCRIPTION

FIG. 1 is a perspective view of a wick;

FIG. 2 is a front elevation view thereof;

FIG. 3 is a back elevation view thereof;

FIG. 4 is a right side elevation view thereof;

FIG. 5 is a left side elevation view thereof;

FIG. 6 is top plan view thereof;

FIG. 7 is a perspective view of the wick in a candle;

FIG. 8 is a front elevation view thereof;

FIG. 9 is a back elevation view thereof;

FIG. 10 is a right side elevation view thereof;

FIG. 11 is a left side elevation view thereof; and,

FIG. 12 is top plan view thereof.

Any broken line illustration of environmental structure in the drawings is not part of the design sought to be patented. All portions shown in broken lines and any portion of the article between breaks in the design form no part of the claimed design.

1 Claim, 5 Drawing Sheets
